CONTAINER

John W. Meaker, Evanston, Ill.

Application December 13, 1939, Serial No. 309,044

21 Claims. (CL 229—55)

This invention relates to bags, envelopes, wrappings, packaging covers or containers, made of paper or like thin, flexible, substantially air impervious sheet material as distinguished, for example from woven fabrics; the term "container" being used herein to describe this class of articles generically and the term "paper," the type of sheet material, of the character indicated, from which the containers are made.

The container with which the present invention is concerned may be in the class of valve bags, so-called, such for example as shown in United States patent to Bates No. 1,762,292, April 1, 1930, which is typical of a rather large number of bags of this general type; or the containers may be in the class of open mouthed bags; and in either case they may be made of single or multiple ply stock, that is of one or more sheets or envelopes of paper; and in any case they may be made of one or more plies of paper which have been treated to make it waterproof.

The primary object of the invention, broadly speaking, is to make the bag of paper, or its equivalent, which has been formed artificially, and after the paper has been manufactured, with a relatively large number of very minute perforations made by the action of electric arcs so that the paper, in the formation of the perforations is removed by burning, or other effect of the electric arcs to give clean holes having no burrs. Burrs will flatten out and to a greater or less extent close the holes when the contents distend the bag or when the bag is under pressure or when the plies are rubbed against each other; and in the case of minute perforations, made (if that were practical) by mechanical pin pricking or punching, the formation of burrs would be inevitable. Moreover, the punching or pin pricking of perforations in paper necessarily weakens the paper; whereas, in the piercing of the paper with perforations formed by electric arcs, the strength of the paper is not substantially diminished but in some cases appears to be enhanced. As a result of this treatment of the paper (the inherent porosity of which, as manufactured, may be substantially nil or may be high, or at any intermediate point), the bags may be given whatever degree of porosity or air perviousness may be required for the purposes for which the bags are used, as well as a uniform porosity for all bags made from a given lot of the perforated paper.

For example, valve bags for cement have been made heretofore of paper which, because of its

method of manufacture, has a loose texture and is, therefore, more or less porous, so that while filling, the air can escape, not only around the filling spout, which is undesirable, but also through the paper itself. However, this type of what might be called inherently, or naturally, or originally (from its method of manufacture) porous paper is more expensive than some other less porous papers, certain types of kraft wrapping papers, for example, since it has to be made from selected pulp produced from selected woods of more expensive character. These pulps have to be carefully digested and beaten and for longer periods than is the case with other papers, and they must be run through the paper making machine more slowly than is the case with the manufacture of the cheaper grades of paper; the desired porosity depending upon the character and proper arrangement in the web of the cellulose fibers. The difference in price between these inherently porous papers, known as "cement bag" papers, and the ordinary kraft wrapping papers, may be several dollars per ton. Furthermore, the so-called porous papers are not always uniform in their porosity. Frequently they are not and this results in the rejection of some lots for bag making purposes involving, often, quite a loss. The porous papers are likely to be less strong than the cheaper grades of paper, such as some types of kraft or wrapping paper; and they are also usually less water resistant because of the loose structure by means of which the required porosity is obtained.

For certain other purposes paper bags, whether valve bags or open mouth bags, should be readily air pervious; for example, to admit air to the contents where such ventilation is necessary to the keeping quality of the contents; and to allow escape of air to prevent bursting when the bag is dropped or otherwise roughly handled.

According to this invention, the paper from which the bag is to be made, or the bag itself, after or during the process of being made up, is formed with a relatively large number of minute perforations, of the character described, the size and number per unit of area being varied as desired, so that the bag, taking account of the original, natural or inherent porosity, or absence of porosity, of the paper, may be made as porous and as uniformly porous as required for the purposes for which the bags are to be used, and this without substantially reducing the strength of the paper.

A further object of the invention is to provide

a bag or other container, either of the single or multiple ply type, and either of the valved or open mouthed or other type of bag, which shall contain one or more plies of water-proofed or moisture-resistant paper, and, by perforating such ply or plies, make the bag pervious to air without substantially diminishing its waterproof character. This may be accomplished by treating paper of the waterproofed type, paper that has been sized, loaded, coated or impregnated with a waterproofing material, for example asphaltum or asphalt compounds and which, because of its method of manufacture or subsequent treatment, is substantially impervious to air, so as to perforate such paper with holes so small in diameter that, without pressure, water will not penetrate into the bag through them, or to any considerable extent, atmospheric moisture, but which, nevertheless, because of the number of such perforations, will allow egress and ingress of relatively large quantities of air. The invention in this aspect solves a difficult problem presented by the packaging, in valve bags, for example, of material which is likely to be damaged in handling and shipping by contact with water or humid atmosphere. Bags for this purpose have been made of waterproofed material but this entails either a very slow filling operation or the risk that some of the bags will burst due to pressure of the confined air. For example, a waterproof paper, which, when tested on the densometer (the machine commonly used for testing the porosity of paper) may give as low a porosity index as 196 seconds, indicating a practically air impervious paper, if perforated according to the present invention may be given any desired degree of porosity, as high, for example, as 5 seconds, without appreciably affecting the waterproof character of the paper. That is, the paper may be substantially as waterproof as the original paper and yet will be as porous as will be necessary for use in the making of valve bags, or for other purposes where the heretofore naturally contradictory characteristics of porosity and imperviousness to water may be desirable. In fact, the porosity of the electric arc pierced paper may be greater than the porosity of the inherently porous paper (cement bag paper) without bringing about any substantial diminution of the waterproof characteristics of the electric arc pierced paper.

The densometer referred to above consists of a pair of telescoping cylinders, the inner movable cylinder having an opening covered by the paper tested and being graduated for air volumes of 100 cubic centimeters. The air can escape only through the paper, under pressure of the weight of the inner cylinder, and the number of seconds required for 100 cc. of air to pass through the paper is, therefore, a negative index of porosity. Ordinary so-called porous cement bag paper of 50 pounds per ream, when tested by this machine may have porosities ranging from 20 to 30 seconds.

In the case of the use of perforated waterproof paper in a multiple ply valve bag, it will ordinarily be sufficient to make one ply only of the perforated waterproof paper. The other plies can be advantageously made, in the interest of economy, of naturally porous paper or non-waterproofed paper which has been electrically perforated in accordance with the present invention.

The perforating operation may be performed by an apparatus such as is shown in United States patent to Irven H. Wilsey No. 1,790,452,

patented January 27, 1931. With this apparatus the paper is moved between spaced electrodes formed, arranged and operated to produce arcs which pass through the paper making minute holes therein. The spacing of the holes may be varied by the design of the electrodes and by the speed of movement of the paper through the machine; and the size of the perforations may be varied to any practical extent by varying the current intensity of the arcs or by other suitable means. Naturally these perforations will be small enough, depending upon the character of the material to be packaged, to prevent the sifting out of any substantial quantity of material, but sufficiently large, or at least sufficiently numerous, to allow the quick voiding of air when the bag is being filled or, if, after filling, the bag is accidentally dropped, or to make the bag suitable for other ventilating purposes.

The size of the perforations may vary, for example, from about $\frac{1}{200}$ to $\frac{1}{100}$ of an inch in average diameter. The number may vary from ten to one hundred per square inch, more or less. The pattern or spacing of the openings will ordinarily be quite irregular. However, the invention is not limited to these particulars, which are merely preferential and illustrative. The holes though small are clean cut, without burrs and tests indicate that they do not materially lessen the strength of the paper as shown, for example, by comparative Mullen tests. Pin pricking the paper, a difficult operation mechanically and one which is not easily susceptible of regulation in respect to the size and number of the holes, would ordinarily involve not only the formation of burrs, which flatten out and close the openings but also a considerable weakening of the structure of the paper. The fact that the electric arc pierced perforations do not appreciably reduce the strength of the bag material, as would be the case with punched or mechanically made holes, is probably due to the fusion or plasticizing of the material around the perforations so as to bond together, or to the rest of the paper, the severed fibers giving clean cuts and reinforced edges in distinction to the burred and frayed edges of pin pricked or other mechanically punched perforations. As a matter of fact the electric arc pierced perforations appear in some cases at least to strengthen rather than weaken the paper.

The invention is illustrated in the accompanying drawing, in which

Fig. 1 is a side view of a valve bag of the sewn type;

Figs. 2 and 3 are sectional views, with the scale much enlarged, on lines 2-2 and 3-3 of Fig. 1, respectively;

Fig. 4 is a very much enlarged view, such as might be seen under a strong microscope (except that the cellulose fibers are not shown) of a small area of the side wall of a bag to illustrate a typical spacing of the perforations; and

Fig. 5 is a section on line 5-5 of Fig. 4.

It is usual to make paper valve bags of several plies. The drawing shows a four ply bag, consisting really of four bags or envelopes, one inside the other. The invention, however, is not limited to any particular number of plies. The bags might be made of two, three, four or five plies, or even of one ply, although the single ply bags would not be suitable for certain materials. In the case of a multiple ply construction, the bag consists of a plurality of paper tubes, one

within the other, the vertical edges of which are overlapped and pasted together, preferably, in staggered relation as indicated at 10, 11, 12 and 13 (Figs. 1 and 3). The upper and lower edges of the paper, that is, the open ends of the tubes, are bound together by binding strips 14, 15 sewn to the paper constituting the body of the bag, by stitching 16-16. At one upper corner of the bag, the material is turned inwardly to form an opening 17, which is closed through pressure of the material, when the bag is filled, by the valve members 18, constituted by the inturned portions of the body.

The invention is not limited to this particular type of bag which is shown merely for the purpose of illustration.

While the average size of the perforations and average number per unit area, when the perforations are made electrically as above described, may be regulated with considerable accuracy, the relative positions of the perforations will ordinarily not be uniform due to the fact that the arcs do not go through the paper in a straight line from one electrode to the other, but appear to be considerably deflected; and this gives a different "perforation" pattern, in different parts of the paper treated and has the advantage that in the case of multiple ply bags the perforations in different plies do not register, as illustrated in Figs. 4 and 5, so that in case the finest of the pulverulent material should sift out of the inner ply it is almost certain to be trapped by the outer ply or plies.

This application is in part a continuation of, and a substitute for applicant's copending application for "Perforated paper container," filed January 23, 1939, Serial No. 252,360.

I claim:

1. An air pervious bag closed except for a relatively small valved filling opening to snugly receive a filling spout adapted to contain pulverulent material comprising at least one envelope of material which as manufactured is substantially impervious to air but which is provided with a large number of electric arc pierced, burrless perforations minute enough to prevent any substantial amount of pulverulent material from sifting out of the bag or any substantial amount of moisture from penetrating into the bag therethrough, while sufficient in number and spaced closely enough together and over a large enough area of the envelope to allow free escape of air from the bag when the bag is filled by the forcing of material through its valved filling opening.

2. An air pervious bag closed except for a relatively small valved filling opening to snugly receive a filling spout adapted to contain pulverulent material comprising at least one envelope of waterproofed material which as manufactured is substantially impervious to air but is provided with a large number of electric arc pierced, burrless perforations minute enough to prevent any substantial amount of pulverulent material from sifting out of the bag or any substantial amount of moisture from penetrating into the bag therethrough, while sufficient in number and spaced closely enough together and over a large enough area of the envelope to allow free escape of air from the bag when the bag is filled by the forcing of material through its valved filling opening.

3. An air pervious container comprising at least one envelope of waterproofed material which, as manufactured, is substantially impervious to air, but which is provided with a large number of electric arc pierced, burrless perfora-

tions minute enough to prevent water, except under pressure, or any substantial amount of atmospheric moisture from penetrating into the bag therethrough, while sufficient in number and distributed closely enough together and over a large enough area to make said envelope substantially porous in respect to the passage therethrough of air.

4. An air pervious container comprising at least one envelope of waterproofed material which, as manufactured, is substantially impervious to air, but is provided, over a major portion of its area, with a large number of electric arc pierced, burrless, perforations minute enough to prevent water, except under pressure, or any substantial amount of atmospheric moisture from penetrating into the bag therethrough, while sufficient in number and distributed closely enough together to make said envelope substantially porous in respect to the passage of air therethrough.

5. An air pervious container comprising at least one envelope of waterproofed material which, as manufactured, is substantially impervious to air, but which is provided with a large number of burrless perforations in average diameter from about $1/200$ to about $1/100$ of an inch and in distribution from about 10 to 100 per square inch whereby the air perviousness of said envelope is substantially increased.

6. An air pervious paper container comprising an envelope provided with a large number of burrless perforations in average diameter from about $1/200$ to about $1/100$ of an inch and in distribution from about 10 to 100 per square inch whereby the air perviousness of said envelope is substantially increased.

7. A paper bag closed except for a relatively small valved filling opening to snugly receive a filling spout, adapted to contain pulverulent material and formed with a large number of electric arc pierced, burrless perforations minute enough to prevent any substantial amount of pulverulent material from sifting out of the bag therethrough but sufficient in number and spaced closely enough together and over a large enough area of the bag to substantially increase the air perviousness of the bag, whereby, through escape of air through said perforations the filling of the bag is facilitated, and in handling the bag, internal bursting stresses are reduced.

8. A multiple ply paper bag closed except for a relatively small valved filling opening to snugly receive a filling spout, adapted to contain pulverulent material, the several plies of which are formed with a large number of electric arc pierced, burrless perforations minute enough to prevent any substantial amount of pulverulent material from sifting out of the bag therethrough but sufficient in number and spaced closely enough together over a large enough area of the bag to substantially increase the air perviousness of the bag, whereby, through escape of air through said perforations the filling of the bag is facilitated, and in handling the bag, internal bursting stresses are reduced.

9. A paper bag closed except for a relatively small valved filling opening to snugly receive a filling spout, adapted to contain pulverulent material and formed with a large number of electric arc pierced, burrless perforations minute enough to prevent any substantial amount of pulverulent material from sifting out of the bag or water or any substantial amount of atmospheric moisture from entering the same therethrough but sufficient in number and spaced closely

enough together and over a large enough area of the bag to substantially increase the air perviousness of the bag, whereby, through escape of air through said perforations the filling of the bag is facilitated, and in handling the bag, internal bursting stresses are reduced.

10. A paper bag closed except for a relatively small valved filling opening to snugly receive a filling spout, adapted to contain pulverulent material and formed with a large number of electric arc pierced perforations having clean cut, burrless edges which are given increased resistance to rupturing stresses through the action of the electric arcs so that the perforations do not substantially diminish the strength of the paper, are minute enough to prevent any substantial amount of pulverulent material from sifting out of the bag therethrough but which are sufficient in number and spaced closely enough together and over a large enough area of the bag to substantially increase the air perviousness of the bag, whereby, through escape of air through said perforations the filling of the bag is facilitated, and in handling the bag, internal bursting stresses are reduced.

11. A paper bag closed except for a relatively small valved filling opening to snugly fit a filling spout, adapted to contain pulverulent material and formed over a major portion of its area with a large number of closely spaced electric arc pierced burrless, perforations minute enough so that any substantial amount of pulverulent material is prevented from sifting out of the bag therethrough but sufficient in number to substantially increase the air perviousness of the bag, whereby, through escape of air through said perforations, the filling of the bag is facilitated and, in handling the bag, internal bursting stresses are reduced.

12. A paper container formed with a multitude of minute, widely distributed electric arc pierced perforations characterized by clean cut, burrless edges which are given increased resistance to rupturing stresses through the action of the electric arcs whereby the perforations of the paper, while materially increasing the air perviousness of the container, does not substantially diminish its strength.

13. A paper bag closed except for a filling opening adapted to snugly fit a filling spout formed with a multitude of minute, widely distributed electric arc pierced perforations characterized by clean cut, burrless edges which are given increased resistance to rupturing stresses through the action of the electric arcs whereby the perforation of the paper, while materially increasing the air perviousness of the bag and thereby facilitating the filling of the same, does not substantially diminish its strength.

14. A paper container formed with a multitude of minute, widely distributed electric arc pierced perforations which add materially to the air perviousness of the container without substantially diminishing its strength.

15. Method of treating the paper of a paper container to increase the air perviousness of the container, without substantial decrease in its strength, which comprises: piercing the paper constituting the container with a large number of minute, widely distributed perforations made by the action of electric arcs whereby a constituent of the paper is acted upon to form strengthening ring-like bodies of dense material around said perforations.

16. Method of treating the paper of a paper container to increase the air perviousness of the container, without substantial decrease in its strength, which comprises: piercing the paper constituting the container with a large number of minute, widely distributed perforations made by the action of electric arcs.

17. A paper container which for the major portion of its area is formed with a multitude of minute, electric arc pierced perforations which add materially to the air perviousness of the container without substantially diminishing its strength.

18. A paper container which for substantially its entire area is formed with a multitude of minute, electric arc pierced perforations which add materially to the air perviousness of the container without substantially diminishing its strength.

19. An air pervious paper bag provided with a relatively small filling opening adapted to snugly fit a filling spout and comprising: an envelope formed with a multitude of electric arc pierced perforations characterized by burrless, clean cut and strengthened edges, which perforations are in average diameter from about $\frac{1}{200}$ to about $\frac{1}{100}$ of an inch and in distribution from about 10 to 100 per square inch over a major portion of the area of said envelope, whereby the air perviousness of the envelope is substantially increased without substantial diminution of the strength thereof.

20. An air pervious paper container comprising: an envelope formed with a multitude of electric arc pierced perforations characterized by burrless, clean cut and strengthened edges, which perforations are in average diameter from about $\frac{1}{200}$ to about $\frac{1}{100}$ of an inch and in distribution from about 10 to 100 per square inch over a major portion of the area of said envelope, whereby the air perviousness of the envelope is substantially increased without substantial diminution of the strength thereof.

21. Method of making paper containers which comprises: providing a web of strong relatively dense paper; piercing said web with a large number of minute widely distributed perforations through the action of electric arcs; and forming containers from said treated web in such manner that the containers have greater air perviousness than the original web but with substantially the same strength.

JOHN W. MEAKER.
